UNITED STATES PATENT OFFICE

2,379,903

PONTOON UNIT FOR FLOATING DRY DOCKS

Frederic R. Harris, New York, N. Y.

Application April 9, 1943, Serial No. 482,375

11 Claims.

(Cl. 114—46)

This invention covers a pontoon unit for a floating dry dock that has a pontoon hull and wing or side walls. The invention relates more especially to means for providing communication for different parts of the unit with other parts, and with the outside air.

The unit comprises a hull and side wall sections across it at bow and stern, movably attached in position; and the dry dock is set up by first raising the wall sections to the vertical on the decks of the hulls, placing the hulls side by side, and then securing the hulls and sections together to form in effect a continuous hull and side walls extending from end to end of the dock. The dock itself and the apparatus for operating and controlling it are fully described in my applications, Serial No. 482,376 for patent on a Multiple unit floating dry dock, and Serial No. 482,374 for patent on Floating dry dock and pumping apparatus respectively, both filed of even date here-with, and defined in the claims appended thereto.

One object of the invention is to provide a dry dock unit having a pontoon hull with a buoyancy chamber therein, power generating apparatus in the buoyancy chamber, and means by which the chamber is ventilated and the exhaust of the power apparatus evacuated through the wall sections, so that the power generating apparatus is still in communication with the atmosphere when the dock is submerged. The invention includes a separate exhaust line for power exhaust running through the wall sections. These are folded down or lowered to the deck when the unit is to be transported from one location to another. The pontoon unit preferably has a ship-shape, and propulsion mechanism driven by the power apparatus, so that the unit can travel as a ship. Even when not equipped to generate its own power, the fair form of the hull permits the unit to be towed at reasonable speed.

Another object of the invention is to provide a dry dock pontoon unit with a buoyancy chamber and crew's quarters therein, and with access to the crew's quarters afforded through passageways in the wall sections of the pontoon unit.

Other features of the invention reside in a stairwell or tower for access to the inside of the pontoon unit from a platform or deck at the top of each wall section; and an exhaust pipe or conduit carried up the stairwell at the center of a spiral staircase. The stair towers and exhaust pipes at their lower ends are blanked or closed when the sections are down.

An additional feature of the invention is the

overlapping of the sides of the buoyancy chamber by the upper ends of the wall sections when the latter are in folded position. Extra communication may thus be provided between the buoyancy chamber and wall sections. This construction makes it possible to use portions of the wall sections as cabins when the sections are lowered for sea-going. Other objects, features, and advantages of the invention will appear or be pointed out as the description proceeds.

A further feature provides alternative passageways and an air supply for service whether the unit has its wall sections down for sea-going or raised for docking; and a system of conduits which can easily be converted and maintained in operation when the wall sections are changed from one of the above mentioned positions to another.

In the drawings on which the same reference characters denote the same parts in all the views:

Figure 1 is a side view, partly broken away to reveal the inside, showing in outline a pontoon unit for a dry dock in accordance with this invention.

Figure 2 is a top plan view of said unit, partly broken away to expose the interior.

Figure 3 is an enlarged sectional detail view showing the connection between the stairwell or tower in a wall section and the gallery or passageway in the hull, the latter leading to the buoyancy chamber, and

Figure 4 is a sectional view taken on the line 4—4 of Figure 3.

The unit includes a pontoon hull 10 in which are bulkheads, some of which form a central buoyancy chamber 11. The special construction is not a part of this invention. The pontoon has a deck 12 and wall sections 13 and 13' that are connected to the deck 12 along their lower inside corners by hinges 14 and 14'. The sections 13, 13' can therefore be lowered into the broken line positions shown in Figure 1.

These hinges are fully described in my aforesaid application relating to the Multiple unit floating dry dock. When in folded position, the inner face of each section is substantially parallel with the pontoon deck 12.

A number of similar pontoon hulls 10 are connected together, side by side, with their wall sections 13, 13' upright and in line, as above stated, to form a dry dock. In the preferred form of the invention, each of the hulls is shaped somewhat like a ship; that is, the ends are of reduced width, and the hull of fair form so that each unit can travel through the water as a ship

when moving the dock to the location at which it is to be assembled. In order to increase the stability of the unit and make it more seaworthy, the wings 13, 13' are caused to lie down on the deck when the dock unit is in transit.

There is power generating apparatus comprising units 16 and 16' in the buoyancy chamber to drive one or more propellers 17 through suitable transmitting means not illustrated herein. The power units are shown diagrammatically in Figures 1 and 2. These power units or plants also operate the pump system, as set forth in my aforesaid application covering a Floating dry dock and pumping apparatus. Arrangements are made for circulating air through the power plants, chamber and wall sections, and for the exhaust of products of the power plants through each wall section, one of which is used for each power plant. The connections include air passages and exhaust pipes which lead from the chamber to the upper ends of the wall sections, so that they extend above the water line of the dry dock, even when the dock is submerged. Each wall section is provided with a platform or deck 20 inside, near the top. This deck is made airtight and water-tight. The spaces over the decks 20 are always above water, for the dock is never submerged entirely.

The air inlet passages include inlet members or funnels 21 extending upward from the top of the wall sections 13 and 13' and stairwells 22, that lead from the decks 20 down to the bottoms of the sections. Each stairwell communicates with gallery 23 in the pontoon hull, attached to the underside of the deck and comprising bulkheads 24, 25 and 26, fixed to internal framing 27. Each gallery or passageway 23 is closed at one end by a partition 28 (see Figures 1 and 3) that forms the bottom of the stairwell, and the other end of the passageway 23 opens into the buoyancy chamber 11.

An exhaust pipe 30 leads from each power plant along the upper portion of the passageway 23, and through the adjacent stairwell 22. It is bent up at the bottom of the stairwell and jointed to a vertical portion thereof at the axis of the stairwell. Each exhaust pipe has an outer jacket and heat insulating material between it and the exhaust pipe proper. There is a spiral staircase 31 in each stairwell, and the steps thereof are connected at their outer ends to the wall of the stairwell; and at their inner ends to the jacket of the exhaust pipe 30, down to the deck level, from which a column 30' in line with the vertical part of the pipe supports said inner ends between the deck and the bottom of the passage 23.

The upper end of each exhaust pipe 30 passes through the deck 20 and connects with a cross-pipe 33 projecting horizontally from the wall section at both sides. At the outer side of the wall section this pipe 33 is connected with an exhaust flue pipe 34 by an elbow 35. On the opposite side of the wall section, the end of the pipe 33 is closed or blanked by a disk 36, bolted or otherwise secured to the flanged end of the cross-pipe 33, when the wall section is in standing position.

When the wall sections 13 are lowered to broken line positions in Figure 1, the blanking disks 36 are removed and the one end of each conduit or pipe 33 then registers with and is connected to a branch 37 of the exhaust pipe 30, which extends through the top of the passageway 23. The branch 37 is closed at other times. At the outer end of each pipe 33, the elbow 35 is then removed and the flue pipe 34 connected directly to the pipe 33 as shown in broken lines in Figure 1.

The disjointed ends of the pipes 30 in the wells

22 are shut by blanks or closures when the wall sections are to be lowered down on the deck; and the openings through the deck for the stairwell 22 and at the bottom of the wells in each wall section are also blanked or closed when the wall sections are lowered.

Each air funnel 21, through which air is drawn into a wall section above the decks 20, is moved from the solid line position at the top of the wall section to the broken line position in the outer side or top of the wall section when the latter is lowered; being then joined to a neck 21'; which is closed when the section is standing. The stairwell passageway 23 and hatchway 50 also form air supply connections through the wall sections to the chamber 11 from the inlet members 21 when the wall sections are either raised or down, respectively.

When the wall sections are in prone or upright position, any suitable means for shutting pipe ends or other openings not needed may be utilized. Such means may be plates, disks, or other closures; and may be bolted or welded in place. To remove or attach such closures, proper tools or a welding torch only are needed.

Stale air is withdrawn from the buoyancy chamber 11 through conduits 40 formed by partitions 41 along the upper part of the passages or gangways 23. Each conduit 40 unites with a pipe 42 in the wall section, and has an outlet extremity 43 at the top. The lower end of each pipe 42 is connected with a neck 45 on the conduit 40 by an elbow 44 when the wall section is vertical. When the section is lowered, the elbow 44 is removed, and the pipe 42 is connected with the air conduit 40 by a branch 46 of the pipe 42 and a branch 47 leading from the conduit 40. The necessary pipe and branch ends are closed accordingly, as the wall sections are vertical or horizontal, in the manner set forth above.

The power exhaust and air discharge conduits are thus readily convertible to serve with the wall sections, either vertical or horizontal.

The hatchway 50 in the deck 12 opens into crew's quarters 51 in the buoyancy chamber 11, above the machinery or power generating space thereof. The deck 30a that separates the machinery room from the crew's quarters has as many openings 30b as are needed through which air can circulate, so that the same air supply and air outlet lines serve for both the machinery room and crew's quarters. The air is preferably caused to flow through the air inlet and air outlet connections by suitable blowers (not shown). The use of blowers for ventilation passages is well understood and their illustration, therefore, unnecessary.

The wall sections when folded down on the deck 12 overlap with their tops the buoyancy chamber 11; and section 13 has an opening in the side near the top over the hatchway 50; so that persons can pass to and from the crew's quarters. The compartment in the wall section above the deck 20 serves as a cabin when the wall sections are down. Hatchways to both sections may of course be used. The openings in the wall sections and for the hatchway in the deck are closed when the wall sections are up.

Both the wall sections have air passages and pipes, so as to have a dual system with effective passageways through either wing wall when the other is being folded or raised; an operation that is preferably performed by buoyancy and that involves partial submersion of the dry dock unit. For such a purpose the tops of the wall sections

preferably have ducts or flues 52 connecting the space in the wall sections below the decks 20 with the outside atmosphere; then as water flows into the section and out no air is trapped above it. Each section also has one or more openings 54 in the bottom to register with openings in the pontoon deck; the function of these openings or ports being described in each of my co-pending applications aforesaid.

Changes and modifications can be made in the illustrated embodiment without departing from the invention as defined in the claims.

Having described my invention, what I believe to be new and desire to secure and protect by Letters Patent of the United States is:

1. A dry dock unit comprising a pontoon hull, a power plant in the hull, a hollow wall section movably mounted on the hull, a conduit extending from said plant through the section in one position for the discharge of exhaust products from said power plant, and means for reconnecting said conduit when the wall section is in a different position.

2. A pontoon unit comprising a hull divided into compartments, a hollow wall section movably mounted on said hull to assume raised or lowered position, means forming a closed-in passageway separate from said compartments between the wall section and the interior of the hull in each position of said section, and means forming a passageway between said section and the interior of said hull in another position of said section.

3. A unit for a dry dock comprising a pontoon hull, a wall section mounted on the pontoon and movable to upright position or lowered position on the hull deck, and means forming alternative passageways between the wall section and inside of the hull when the wing walls are lowered and when they are in upright position, for use according to the position of the section.

4. A dry dock pontoon unit having a hull, a wall section thereon, a closed-in stairwell in the section, a power plant in the hull, means forming a passageway between the power plant and the stairwell, an exhaust pipe in the passageway leading from the power plant and extending upward through the stairwell, and stairs in the well around the exhaust pipe.

5. A dry dock pontoon unit comprising a hull having a chamber, a hollow wall section movably mounted on the hull to assume upright or lowered position, a stairwell in the wall section, means forming a passageway between the chamber

and the section, when the section is upright, and a removable hatchway to connect the chamber to the wall section when the latter is lowered.

6. A dry dock pontoon unit having a hull with a deck and containing a chamber within it, a wall section on the hull movable to upright position, or to prone position in such relation to the chamber that a portion of the section extends over the chamber, and a hatchway between the hull and the chamber when said section is in prone position.

7. A dry dock pontoon unit comprising a hull, a hollow movable wall section on the hull, a conduit within the hull, a conduit extending through the wall section, and means for connecting said conduits in different positions of the wall section.

8. A dry dock pontoon unit having a hull containing a chamber, a movable hollow wall section on the hull, said section having an air conduit therein, and an air discharge conduit connecting the chamber to the conduit in the section in one position, said conduits having means for reconnecting the conduits in a different position of the wall section.

9. A dry dock unit including a pontoon hull, a wall section movable thereon, to assume raised or lowered position, means forming a passage and conduits connecting the inside of the hull to the inside of the section in one position of the latter, means for forming another passageway and parts for converting said conduits for continued use when the wall section changes position.

10. A dry dock unit including a pontoon hull, a hollow wall section movably mounted on the hull to assume upright or lowered position, a stairwell in the wall section, means forming a passageway in the hull united, when the section is upright, to said stairwell, a conduit in the section and a conduit in the stairwell, a cooperating conduit in the hull for each of said conduits, means connecting the conduits in the stairwell and section to those in the hull when the section is upright, and means comprising branches and other parts on said conduits for reconnecting the conduits and closing the lower end of the stairwell and adjacent end of said passageway when the section is lowered.

11. A dry dock unit according to claim 10, having means constituting an alternative passageway to connect the hull and the wall section when said section is in lowered position.

FREDERIC R. HARRIS.
